(57) **CLAIM**

The ornamental design for a weight retention collar, as shown and described.

DESCRIPTION

FIG. 1 is a left, front perspective view of a weight retention collar of the new design;

FIG. 2 is a front plan view of the invention illustrated in FIG. 1;

FIG. 3 is a rear plan view of the invention illustrated in FIG. 1;

FIG. 4 is a right side view of the invention illustrated in FIG. 1;

FIG. 5 is a left side view of the invention illustrated in FIG. 1;

FIG. 6 is a top view of the invention illustrated in FIG. 1; and,

FIG. 7 is a bottom view of the invention illustrated in FIG. 1.

The broken lines in the drawings depict portions of the weight retention collar that form no part of the claimed design.

1 Claim, 6 Drawing Sheets
